UNITED STATES PATENT OFFICE.

AUGUST BERNER, OF MUNICH, GERMANY.

PNEUMATIC POWER-HAMMER.

942,163.

Specification of Letters Patent. Patented Dec. 7, 1909.

Application filed April 13, 1909. Serial No. 493,706.

To all whom it may concern:

Be it known that I, AUGUST BERNER, subject of the German Emperor, residing at Munich, Germany, have invented new and useful Improvements in Pneumatic Power-Hammers, of which the following is a specification.

This invention relates to a pneumatic hammer with two cylinders (a pump and a ram cylinder), the ends of which are connected by passages with one another. In the known forms of construction of such hammers it is necessary in order to govern the working tool as completely and certainly as possible, that each of the two passages connecting the pump and ram cylinders should be provided with a separate governing arrangement. The construction of the hammer is however thereby complicated and its handling rendered more difficult. This invention is intended to remove this disadvantage by the hammer being governed by means of a single slide valve, common to both the connecting passages. The essential parts of one form of construction of a pneumatic hammer arranged in this way are shown in Figures 1-5 of the accompanying drawings.

Fig. 1 and Figs. 5-7 show a vertical section of the hammer made through the middle of the cylinders and slide valve in various positions of the slide valve; while Fig. 2 is a vertical section of the slide valve made at right angles to the central plane of the two cylinders; Figs. 2^a and 5^a are views similar to Figs. 2 and 5, respectively, but showing the valves in different positions. Figs. 3 and 4 are two sections on an enlarged scale made at right angles to one another of the governing slide valve.

As appears from the drawings the pneumatic hammer has a pump cylinder *a* and a ram cylinder *b* separate therefrom; in these cylinders the pump piston *c* and the ram piston *d* which in its upper part is hollow, are respectively arranged in such a way that on both ends of the pistons working chambers *e* and *f* and *g* and *h* respectively are formed. Passages *i*, *k*, *l*, *m*, branch off from the under and upper working chambers *e*, *g*, and *f*, *h*, respectively of the two cylinders, which passages lead to a slide valve arranged between both cylinders and located on an inserted bush *q*. For the purpose of shortening the slide valve as far as

possible, said passages extend to nearly the middle of the valve cylinder before opening into it.

The pump piston is formed as a stepped piston and provided with a hollow trunk *60* or piston rod *p* which is guided in a stuffing box *q*. The upper annular extension of this stuffing box *q* enters the lower part of the pump cylinder *a*, leaving an annular space *e* between it and the walls of the said cylinder *a* and is provided with apertures or ports *r* distributed around its periphery, which ports are uncovered by the hollow piston rod *p* when the pump piston approaches the upper end of its stroke. This arrangement of the holes *r* in the extension of the stuffing box projecting into the pump cylinder allows of piston rings being effectively employed on the hollow piston rod *p*, as any connection of the openings *r* with the outside air is excluded as soon as they are covered by the piston rings on the downward stroke. The pump cylinder has also a deflecting passage *s* which branches off near the cylinder cover and connects again with the cylinder chamber at a distance from its starting point approximately corresponding to the thickness of the piston. In consequence of this arrangement there is always an atmospheric pressure established at the commencement of the downward movement of the pump piston, both in the suction chamber over the upper piston surface and also in the pressure chamber under the lower piston ring surface, and thereby a uniform working of the hammer is produced. The ram cylinder *b* is also provided with a passage *t* forming a continuation of the passage *m*, which passage *t* passes through the cylinder cover and connects with the ram cylinder co-axially with the former. The passage *t* passes upward into the lubricating passage connected with a lubricating vessel *u* placed above and is provided with a non-return valve *v* only opening inward. In the wall of the ram cylinder *b* a passage *w* is also provided, which branches off at a distance from the cylinder cover, which corresponds with the depth of the piston hollow and connects again with the cylinder at a distance from its branching point, coinciding with the height of the piston. At this end of the passage a non-return valve *x* is provided, which is adapted to open only under the

superpressure reigning in the working chamber *g*.

The governing slide valve *o* consists preferably of a cylindrical body and is traversed by two passages *y z* of elongated rounded section, the ends of which are enlarged and the central axes of which extend at a distance from one another corresponding to the distance of the mouths of the 10 passages *i l*, and *k m*, respectively formed in the valve cylinder. The recess lying to the left of the passage *z* merges into the lateral recess *4* lying on the right hand side of the slide valve *o* and extending downward, by the intermediary of openings *3* adapted to be closed by the non-return valve 15 *2*, which recess *4* at its lower end is continued into a perforation *5* leading beyond the middle of the slide and running in the 20 same direction as the passages *y z*. From this perforation *5* a passage *7* branches off, which as regards its diameter coincides with the perforation *5*, and is arranged transversely to the latter, which passage *7* 25 at its end extends into a recess or enlargement *8* widening downward. At the rear side of the slide valve casing Fig. 2, a perforation *9* leads to the outside, which is also closed by a valve *10* opening inward only. 30 A pipe *11* (Fig. 2) connecting with the interior of the ram cylinder is also connected with the valve casing, which pipe by the displacement of the slide valve may be placed in communication with the open air 35 by means of a passage *12* which crosses it transversely and an aperture *13* provided in the valve casing. The slide valve has in addition a small passage *6* which also connects with the outside and which may be 40 connected with the passage *k* of the ram cylinder.

The pump piston is operated in known manner by means of a rocking crank gear 45 *14, 15*, while for displacing the distributing valve a lever mechanism *17, 18, 19*, pivotal on a fixed pin *16* is provided. If regular heavy blows are to be given, the distributing slide valve is so adjusted that the central axes of its ports *y z* coincide with the 50 centers of the mouths of the connecting passages *i k* and *l m* (Fig. 1) which mouths are situated in the valve casing.

The hammer described works as follows:— When the pump piston is at the upper end 55 of its stroke the ports *r* of the stuffing box are uncovered by the hollow piston rod *p*, so that there is atmospheric pressure in the working chamber *e* and also, by the arrangement of the passage *s*, in the working chamber *f*. After a small downward movement 60 of the pump piston these ports *r* are covered by the piston rod, so that in the lower pump chamber *e* there is compression, but in the upper chamber *f* a partial vacuum, 65 and the ram piston, in consequence of the

connection of the working chambers *g h* of the ram cylinder with those of the pump cylinder, is lifted. As a partial vacuum is formed in the working chamber *h* over the ram cylinder, the ram piston *d* is thrown upward until it is close to the cover, under the action of the effective pressure on its under side, and the momentum imparted to it, until there is produced there the necessary compression for forming an air cushion. The recoil resulting therefrom would, however, be too hard and under certain circumstances even dangerous. In order to avoid this drawback and to obtain a sufficiently effective air cushion the side passage *w* is provided, the non-return valve *x* of which is opened as soon as the lower edge of the piston has passed over its mouth. Compressed air then flows through this passage *w* into the working chamber *g* and produces in the chamber *h* a sufficiently effective air cushion. After the pump piston has reached the lower end of its stroke, it again rises, so that expansion of the air and a diminution of pressure takes place in the 85 lower working chambers *e* and *g* of the pump and ram cylinders respectively and the ram can drop freely. This falling movement is assisted by the expansion of the previously compressed air cushion above 90 the ram piston *d*. As soon as the pump piston again approaches the upper end of its stroke, the ports *r* are again uncovered and atmospheric pressure is again reestablished above and below the pump piston. 100

For the purpose of giving light blows, the slide valve is displaced upward in such a way that the passage *l* is placed in communication with the outer air through the passage *y* of the slide valve and the pipe *11* coinciding with the transverse perforation or port *12* of the slide valve (Fig. 3). By this means on the one hand the suction action produced by the working chamber *f* relative to the ram piston is considerably 110 diminished, while on the other hand the compressed air expelled from the working chamber *e* and which operates the lifting of the ram piston, escapes from the working chamber *g* as soon as the lower edge of the 115 ram piston has passed the mouth of the pipe *11*. Consequently the ram piston does not rise to its entire height of lift and the suction action on the same for the downward movement only again takes place when it 120 has again covered the mouth of the pipe *11*.

If the ram is to be kept raised, the slide valve is displaced so much farther upward that the central axis of the non-return valve *2* lies about at the same height as the mouth of the passages *i k*, and the connecting passage *l* is in direct communication with the external air by the intermediary of the passage *y* of the slide valve and the recesses provided at its ends. The recess *8* at the end 125

of the passage 7 of the slide valve has also moved in front of the opening 9 of the valve 10 mounted on the slide valve casing. In consequence of this position of the slide valve no suction action is exerted on the upper end of the ram piston by the reciprocating pump piston. On the pump piston *c* rising, however, fresh air is always drawn through the valve 10 and the passages 9, 8, 10 7, 5, 4, *i*, into the working chamber *e*, which air is compressed on the descent of the pump piston and forced into the working chamber *g* under the ram cylinder. In order to depress the ram, a further displacement of the distributing slide valve is effected by the lower edge of the passage 6 being turned with respect to that of the passage *k* and the passage *z* carrying in its lower recess the pressure valve 2, being brought into communication with the passage *m* of the ram cylinder *b*. In the upward movement of the pump piston, similarly to when the ram is held up, air is drawn through the valve 10 and the passages 9, 8, 7, 5, 4, *i*, into the working chamber *e*. On the descent of the pump piston on the other hand the compressed air is forced into the working chamber *h* through the passages *i*, 4, 3, *z*, *m*. As air also escapes from the working chamber *g* into the open through the passage 6 on the movement of the pump piston, and this escape of air only takes place slowly, the ram is gently placed on the workpiece and then firmly pressed thereon.

It is of essential importance both in the holding up as well as the depression of the ram, that the pressure action should take place in both cases merely at the lower annular face of the pump piston. It is thereby rendered possible to produce a considerably higher pressure on the rams when they rest on the workpiece in a position of repose, than if the upper face of the pump piston produced the pressure on the ram, and the expenditure of power by the hammer is reduced because in this case only the annular face of the pump piston acts under pressure, whereas if the same pressure was employed against the much larger upper face of the pump piston the effect would be much reduced. In order to prevent too great an increase of the pressure, a safety valve 20 is provided at the end of the working chamber *e*, through which valve the compressed air blows off as soon as the pressure attains a height which is inadmissible for practical reasons.

I declare that what I claim is:—

1. In a pneumatic hammer, a pump cylinder, and a stuffing box cylinder of smaller diameter engaging one end of the pump cylinder, in combination, with a stepped piston fitting into the pump cylinder at one end and having a trunk fitting in and 65 adapted to slide in the stuffing box cylinder,

said stuffing box cylinder being provided with a communication leading into the annular space between the pump cylinder and the piston trunk, and arranged at a point where it will be exposed when the pump piston arrives near the end of its forward stroke, a communication between the head of the pump cylinder space and an intermediate portion of said cylinder space, adapted to be opened by the piston near the end of its forward stroke.

2. In a pneumatic hammer, a pump cylinder having a communicating passage between its head and an intermediate portion, and a stuffing box cylinder of smaller diameter engaging the end of the pump cylinder, extending a short distance within the same to form an annular space with the said pump cylinder, and provided with a series of ports extending from the interior of the said stuffing cylinder into the said annular space, in combination, with a stepped piston having an annular forward portion fitting into the pump cylinder, and a hollow trunk portion fitting into the stuffing box cylinder, the annular forward portion and the hollow trunk portion of said piston being of such length as to open the ports and the communicating passage at a point near the end of its forward stroke.

3. In a pneumatic hammer, an air compressing pump, a ram-cylinder, a ram piston adapted to reciprocate within the same, and a casing containing a valve device for controlling the communication between the upper and lower cylinder spaces of the pump and the ram, in combination, with a duct connecting an intermediate part of the ram cylinder with the valve casing, and a port in the valve device adapted to register with said duct, when the valve device has been shifted into the proper position.

4. In a pneumatic hammer, an air compressing pump, a ram cylinder, a ram piston adapted to reciprocate within the same, and a valve cylinder arranged between the two and having ports for the communication between the forward and rear portions of the cylinder spaces of the pump cylinder and the ram cylinder, in combination, with a duct leading from an intermediate portion of the ram cylinder into the valve cylinder, and a slide valve slidably arranged within the valve cylinder and provided with communicating passages adapted to register with the ports of the same and with a transverse passage leading to the exterior and adapted to register with the said duct, whereby the ram piston may be raised only to a portion of its stroke.

5. In a pneumatic hammer, a ram cylinder, in combination, with a ram piston adapted to reciprocate within the same, and means for introducing compressed air into the rear part of the cylinder, the said cyl-

inder being provided with a passage connecting the head of the forward working chamber with an intermediate portion of the cylinder space, a non-return valve being arranged in the said passage and so disposed that the compressed air will be allowed to pass forward into the cylinder head, when the piston has passed the rear opening of said passage, but will be prevented from returning, thereby produc-

ing an air cushion at the head of the cylinder.

In testimony whereof I have signed my name to this specification in the presence of two subscribing witnesses.

AUGUST BERNER.
